Patented Feb. 14, 1922.

UNITED STATES PATENT OFFICE.

ROBERT O. SLATER, OF TULSA, OKLAHOMA.

WIRE-LINE SOCKET.

1,406,768.

Specification of Letters Patent. Patented Feb. 14, 1922.

Application filed March 13, 1919, Serial No. 282,414. Renewed August 19, 1921. Serial No. 493,697.

To all whom it may concern:

Be it known that I, ROBERT O. SLATER, citizen of the United States, residing at Tulsa, in the county of Tulsa and State of Oklahoma, have invented certain new and useful Improvements in Wire-Line Sockets, of which the following is a specification, reference being had therein to the accompanying drawing.

10 This invention relates to line sockets and more particularly to what is known as the swivel type of socket employed in connection with the drilling of oil and gas wells.

It has before been suggested in the art, 15 to which the invention relates, to provide a socket adapted for the reception of the swivel connection for the lower end of the wire or rope, and to interpose between said connection and the wall of the socket yielding-

20 able means whereby to relieve strain on the parts as the stem or tool contacts with the surface operated upon, but in all prior devices, with which I am familiar, objections have manifested themselves, particularly

25 with regard to the unusual strain on the resilient support, and the frequent breakage of the latter, and incident cutting or breakage of the wire or rope.

It is one of the primary objects of the 30 present invention to provide in a device of the character described, novel means of connection between the drilling line and the drilling stem, whereby to permit the stem to rotate freely and at the same time eliminate the objectionable jar incident to contact of the stem with the surface operated upon, 35 whereby to prolong the life of the drilling line; whereby to give more elasticity to the action of the drilling stem, and whereby to protect the yieldable characteristics of the 40 connection against undue strain in use.

In carrying out the invention and improvements, it is proposed to provide a socket, a swivel within the socket, and an 45 interposed spring or other resilient means between the swivel and wall of the socket to permit relative yieldability, and operatively associated means whereby to limit the action of the spring means and protect the 50 latter against breaking under undue strain.

It is a further object of the invention to provide in a connection between the drill

stem and drill line, a novel and improved type of swivel, preferably of a type adapted to protect the spring or cushioning means 55 interposed between the swivel and socket by contact with the wall of the socket prior to the complete compression of the spring or cushioning means.

Again, it is an object of the invention to 60 provide a novel and improved socket useful in the connection described, of a type to protect the wire or rope line against contact with the spring or cushioning means interposed between the swivel and wall of 65 the socket. Said protecting characteristic is preferably present both during the normal operation of the device, and should by any possibility the spring or cushioning means become broken in use when the 70 broken parts would ordinarily have a tendency to cut said line.

Again, it is an object of the invention to 75 provide a yieldable support for the swivel, the said support being interposed between the base of the swivel and the base of the socket.

More particularly, the invention includes a socket member adapted to be connected to the drill stem, the said socket being hollow for the reception of a freely rotatable 80 swivel adapted for connection with the wire or rope line, cushioning means interposed between the base of the swivel and the base of the socket member, and cushioning means 85 also interposed between the top of the socket member and said swivel.

It is further contemplated by the present invention to provide a novel and sufficient shock absorbing means of wear resisting properties, simple and inexpensive in design and operation, strong and durable, highly efficient and satisfactory in use, and to generally improve upon line sockets as 90 heretofore constructed and in use.

95 Other improvements, and novel details in the construction and arrangement of the various parts of the device, will be appreciated by those skilled in the art from the description to follow, which is to be considered 100 in connection with the accompanying drawings forming a part hereof, and wherein is disclosed, for the purpose of illustration, a convenient and satisfactory embodiment

of the invention, though in this connection it is to be borne in mind that many minor changes in details may be resorted to without departing from the spirit of the invention.

In the drawings:—

Figure 1 is a vertical section of a line socket connection embodying my improvements, parts being shown in elevation;

10 Figure 2 is an elevation of a swivel removed;

Figures 3 and 4 are sectional views substantially on the lines 3—3 and 4—4 of Figure 1, respectively.

15 With more particular reference to the drawings wherein like reference numerals refer to corresponding parts throughout the several views, 1 is a member forming a socket, the same being hollow whereby to provide a swivel chamber 2, which said chamber is preferably closed at its lower end by a stem 3 having an abutment shoulder underlying the lower end of the socket 1, and a plug 4 fitted within and having 20 threaded engagement with the interior peripheral wall of the socket. The upper part of the swivel chamber 2 is provided with a shoulder portion 5 surrounding a central, longitudinally extending opening 6 25 adapted for the reception of the wire or rope line 7 which projects below the shoulder 5 of the socket and is adapted for connection with the swivel to be now described.

The wall of the socket surrounding the 30 swivel chamber 2 is preferably circular, and adapted for free longitudinal as well as rotatable movement within the chamber 2, is a swivel comprising a base part 8 and an elongated upwardly extending stem 9.

40 The swivel including the base part and stem is of a length to provide a clearing space between the lower end of the swivel and closed bottom formed by the plug 4 of the socket, and between the upper end of the 45 stem and the shoulder 5 of said socket, and the stem of the swivel is of a diameter greater than the opening 6 for the wire line 7 whereby to underlie the abutment formed by the shoulder 5. The swivel is provided 50 with a central, longitudinally extending opening terminating in a tapered, or conical enlarged part adapted for the reception of the lower end of the wire or rope line. The base of the swivel at its point of connection with the stem 9 constitutes a shoulder

55 10 adapted to constitute an abutment for the lower shock absorbing means, such as a spiral spring 11 sleeved upon the stem 9 and adapted to contact at its upper end with 60 the shoulder 5 of the socket whereby to normally space the upper end of the stem 9 from said shoulder 5.

Also interposed between the lower end of the swivel and closed lower end of the socket 65 is an auxiliary cushioning means which

conveniently takes the form of a spiral spring 12.

The stem part 3 is conveniently provided with a screw-threaded socket 3^a at its lower end adapted for the reception of an inter-engaging threaded upper end 3^b of a suitable tool.

It is believed that the construction and operation of the device will be fully understood from the description above when read in connection with the drawings, but some of the advantages incident to the use of the improved device may be briefly reviewed as follows: The device may conveniently be termed a combination spring and swivel neck connector having exceedingly useful and novel shock absorbing characteristics. The parts are so proportioned that the drilling stem is given the necessary elasticity without causing breaking of the spring during its use, and in this connection it will be observed that the swivel member 8—9 has an extended neck or stem projecting upwardly to a point slightly short of the upper end of the spring when the spring is in its normal or natural position.

When the spring has been compressed by the downward stroke of the device in use, and before the spring is permitted to be entirely compressed, the upper end of the neck or stem 9 of the swivel is brought into contact with the shoulder 5 at the top of the socket, the shoulder thus taking the final and more severe jar in lieu of the spring. It has been ascertained from the use of prior devices that the continual jar completely compresses the spring each time the drilling stem or tool contacts with the surface or bottom of the hole, and this results in breaking the spring after a relatively brief period of use, thus rendering the tool useless, at least so far as any yieldable characteristic is concerned, and then again the broken parts of the spring being brought into contact with the wire or rope, the latter soon becomes cut and severed thereby, with the result that the tool is absolutely useless until new parts are substituted, if the damage has not in fact injured the device beyond repair. In the present device the swivel permits the stem to freely rotate and allows the natural twist to remain in the drilling line. The neck or extension 9 of the swivel not only prevents the drilling line from continual wear on the spring, but, assuming that the spring should by any possibility become broken, this stem 9 would prevent any broken parts from coming in direct contact with the drilling line with the disastrous result above noted. The neck or stem 9 of the swivel is so proportioned in length with regard to that of the spring that it will engage with the shoulder 5 of the socket after a predetermined degree of compression of the spring, and always before the

spring is entirely compressed. The lower spring 12 is provided more particularly to prevent undue wear of the swivel on the closed lower end of the socket.

5. What I claim is:—

1. In a device of the character described, the combination of a tubular socket member, a swivel member positioned within and enclosed by the socket member for relative 10 longitudinal movement, the said swivel member having a rope or cable receiving recess therein and also having a seat for a cushioning means, cushioning means interposed between said seat of the swivel and the 15 top wall of the socket, and said top wall of the socket being adapted to be engaged by the swivel to thereby limit the compression of the cushioning means.

2. In a device of the character described, 20 the combination of a hollow tubular socket member, a swivel member loosely positioned entirely within the socket member for relative longitudinal and rotatable movement, said swivel member having a rope or cable 25 securing means, shock absorbing cushioning means interposed between the swivel and socket members adapted to be compressed on relative longitudinal movement of these parts, and means for positively limiting the 30 compression of the shock absorbing means.

3. In a device of the character described, the combination of a hollow socket member, a swivel member mounted for relative longitudinal movement within the socket member, 35 a line projecting through one end of the socket member and secured directly to the swivel, and means for resisting said relative longitudinal movement comprising a spring interposed between the swivel and 40 socket members and cooperating means for limiting the compression of the spring.

4. In a device of the character described, the combination of an elongated cylindrical part forming a socket, a swivel loosely positioned within the socket for free relative 45 movement, said swivel having an upwardly extending stem normally projecting to a point adjacent to but spaced from the top of the socket, a spiral spring positioned on 50 said stem adapted to abut at one end against the swivel, and at its opposite end against the top wall of the socket, and a wire or rope line projecting through the top wall of the socket and connecting directly with the swivel.

5. In a device of the character described, 55 the combination of an elongated cylindrical part forming a socket, a swivel positioned within the socket, said swivel having an upwardly extending stem projecting to a point 60 adjacent the top of the socket, a spiral spring sleeved on said stem adapted to abut at one end against the swivel, and at its opposite end against the top wall of the socket, a wire or rope line projecting through the 65 top wall of the socket and connecting di-

rectly with the swivel, and cushioning means interposed between the base of the swivel and lower end of the socket.

6. In a device of the character described, the combination of a socket member having 70 side, top, and bottom walls forming a chamber, a swivel member positioned within said chamber, the top wall of the socket and said swivel being provided with a longitudinally extending opening for the reception of a 75 wire or rope line, a spring interposed between the swivel and top wall of the socket, and means for spacing the spring from the wire or rope line comprising an upwardly projecting part on the swivel, said upwardly projecting part on the swivel terminating a relatively short distance from the top wall of the socket whereby to engage 80 said top wall and limit the compression of the spring in the relative longitudinal movement of the swivel and socket.

7. In a device of the character described, the combination of a socket member having 85 side, top, and bottom walls forming a chamber, a swivel member loosely positioned 90 within said chamber, the top wall of the socket and said swivel being provided with a longitudinally extending opening for the reception of a wire or rope line, a spring interposed between the swivel and top wall 95 of the socket, and means for spacing the spring from the wire or rope line comprising an upwardly projecting part on the swivel, said upwardly projecting part on the swivel normally terminating a relatively 100 short distance from the top wall of the socket whereby to engage said top wall and limit the compression of the spring in the relative longitudinal movement of the swivel and socket, and a spring interposed 105 between the base of the swivel and bottom wall of the socket.

8. In a device of the character described, the combination of an elongated cylindrical socket member having side, top, and bottom 110 walls, a swivel loosely positioned within and enclosed by the socket member for relative, free, rotatable and limited lengthwise movement, a spring member interposed between the top wall and the swivel, a spring interposed between the bottom wall of the socket and swivel, and said bottom wall being removable.

9. In a device of the character described, the combination of an elongated cylindrical 115 socket member having side, top and bottom walls, a swivel positioned within the socket member for relative, free, rotatable and lengthwise movement, a spring member interposed between the top wall and the swivel, 120 means independent of said spring for limiting the compression of said spring, a spring interposed between the bottom wall of the socket and swivel, the said bottom wall having a threaded engagement with the side 125

wall of the socket whereby the same may be removed, and said bottom wall having a downward extension with a lowered terminal recess for the reception of a drill stem or tool.

10. In a device of the character described, the combination of an elongated socket member having an internal shoulder part adjacent its top, a swivel member positioned 10 within the socket member for rotatable and lengthwise movement, said swivel comprising a base part, and an elongated stem of reduced diameter projecting upwardly to a point adjacent to but spaced from said 15 shoulder part of the socket, a spiral spring sleeved upon the stem and engaging at its lower end the base of the swivel, and at its upper end said shoulder part of the socket, the said stem being adapted in the relative 20 longitudinal movement of the parts to engage said shoulder and constituting means for limiting compression of the spring.

11. In a device of the character described, the combination of an elongated socket member having an internal shoulder part ad-

jacent its top, a swivel member positioned within the socket member for rotatable and lengthwise movement, said swivel comprising a base part, and an elongated stem of reduced diameter projecting upwardly to a point adjacent to but spaced from said shoulder part of the socket, a spiral spring sleeved upon the stem and engaging at its lower end the base of the swivel, and at its upper end said shoulder part of the socket, 30 the said stem being adapted in the relative longitudinal movement of the parts to engage said shoulder and constituting means for limiting compression of the spring, and an auxiliary spring of relatively different 35 resistance from the first named spring interposed between the base of the swivel and lower end of the socket.

In testimony whereof I hereunto affix my signature in the presence of two witnesses.

ROBERT O. SLATER.
